UNITED STATES PATENT OFFICE.

THORSTEIN HIMLE, OF SANTA ROSA, CALIFORNIA.

LIFE-PRESERVER.

1,108,756.

Specification of Letters Patent. Patented Aug. 25, 1914.

Application filed June 28, 1913. Serial No. 776,328.

To all whom it may concern:

Be it known that I, THORSTEIN HIMLE, a citizen of the United States, residing at Santa Rosa, in the county of Sonoma and State of California, have invented certain new and useful Improvements in Life-Preservers, of which the following is a specification.

This invention relates to improvements in life preservers, and more particularly to life preservers in the form of a garment adapted to fit the wearer, the garment comprising a coat, trousers, helmet and gloves, the coat having the helmet and gloves attached thereto or formed integrally therewith, the trousers being detachably connected to the coat around the bottom thereof through the medium of specially devised water tight fastening means to be hereininafter fully described.

A further object of the invention contemplates the provision of a plurality of water-proof and air tight compartments or balls which, when inflated render the garment buoyant and sustain the wearer upon the surface of the water.

A still further object of the invention resides in the provision of means in the nature of a belt adapted to be formed upon the coat and trousers for fastening the two together, the belt when properly fastened effecting a water tight connection therebetween, the water and air tight compartments being disposed adjacent the waist line of and within the garment to protect the wearer against excess pressure that would otherwise be manifest were the water allowed to force the garment inwardly and against the body.

The invention still further resides in the provision of a life preserver of the character described, wherein the wearer, while sustained upon the surface of the water will have free easy and full use of his limbs, especially formed fastening means to be hereinafter termed garters, being disposed upon the trousers to prevent the air within the garment from entering and collecting within the shoes or foot space thereof.

The above and additional objects are accomplished by such means as are illustrated in their preferred embodiment in the accompanying drawings, described in the following specification and then more particularly pointed out in the appended claims forming a part of this application.

In describing the invention in detail, ref-

erence will be had to the accompanying drawings, wherein like characters denote like or corresponding parts throughout the several views and in which:

Figure 1 is an elevation illustrating the application of the invention; Fig. 2 is an enlarged longitudinally extending view of the belt or fastening means employed in connection with my invention; Fig. 3 is a detail perspective view of the means employed for locking the belt sections together; Fig. 4 is an enlarged elevation of the air tight compartments or balls employed to sustain the garment upon the surface of the water; and Fig. 5 is a cross sectional view of the casing within which the balls are arranged.

Referring now to the drawings, wherein is illustrated, the preferred form of my invention, the numeral 1 designates a coat in its entirety, the said coat having sleeves 2 projecting therefrom and a helmet 3 secured thereto, the latter being stitched or otherwise fastened as at 4 below the collar of the said coat 1. Gloves 5 are secured in any suitable way or manner to the sleeves 2, thus protecting the hands of the wearer in the water yet permitting the use thereof when desired.

A casing 6 is adapted to be detachably secured within the coat 1 of the garment through the medium of cords 7, secured thereto, the latter adapted to pass through openings 8 formed within the casing along the lower edge thereof, the upper edge of the casing having flaps 9 secured thereto provided with button holes 10 adapted to be arranged over buttons (not shown) disposed upon the interior of the coat, the latter with the grooves 7 supporting the casing 6 in the desired manner near the waist line of the wearer. Water tight compartments or balls 11 are arranged in series within the casing 6, the said balls when inflated adapted to render the garment buoyant to sustain the wearer upon the surface of the water. By providing a plurality or series of water tight compartments, the puncture of one, will not destroy the buoyancy of the garment or materially effect its efficiency or sustaining properties.

Secured to the base or bottom of the coat 1 upon the interior thereof, is a band or belt section 12 grooved exteriorly for the purpose of receiving a second belt section 13 likewise secured upon the top or upper edge of the

trousers 14 of the garment, the second belt section 13 being shaped to conform to the configuration of the section 12 for effecting a water-tight connection between the coat 5 and the trousers of the wearer when the said trouser section is arranged over the coat section of the belt and within the groove formed therein. A lever 15 is pivotally secured as at 16, near one extremity of the lower trousers belt section 13, and is employed for the purpose of fastening the said belt section tightly over the coat belt section 12, a lever being further pivoted as at 17 to the opposite extremity of the belt section 13 from that of 10 its pivot point 16, this arrangement causing the two extremities of the said section to overlap, as is clearly shown in Fig. 3 of the drawings, the lever 15 when forced into engagement with the exterior or outer face of 15 the belt is adapted to lock the extremities of the belt section together and the entire section over the belt section 12 of the coat. A flap 18 may be arranged over the meeting ends of the belt section 12 to further render 20 the connection theretwixen waterproof.

To prevent the air within the garment from collecting in its lower portion of the trousers 14, garters designated in their entirety by the numeral 19 have been provided, 30 the said garters comprising a non-elastic strap 20 secured upon the exterior of the trouser legs 14 terminating in a hook member 21 adapted to catch an elastic strap 22 likewise secured exteriorly of the trouser leg, 35 this arrangement of the garter section drawing the trouser legs together and closing communication between the upper and lower portions thereof. The garter is preferably disposed between the knees and the feet of 40 the wearer.

An opening 23 is formed within the helmet 3 through which the face of the wearer is exposed, the material of which the helmet is composed causing the edges of the opening 45 to lie tight against the face of the wearer and thus prevent the entrance of water in the interior of the garment. A light 24 may be arranged upon the top of the helmet 3 and supported thereupon through the medium of a hanger strap 25, the latter adapted to normally fit beneath the chin of the wearer and, when thrown back over the head as is illustrated by the dotted lines in Fig. 1, to cut off the electric circuit necessary 50 for the light, this being accomplished by constructing the said band in a manner suitable for the purpose to which it is designed.

Pockets 26 and 27 may be arranged exteriorly of the garment, the former above 60 the waist line and the latter below, one of the pockets being provided as a lunch receptacle and the other for a water bottle, thereby enabling the wearer of the suit to partake thereof when necessary.

Having described fully, the construction

of the garment, it now remains to set forth the manner in which the same is applied. The coat 1 is first slipped over the head, the arms of the wearer fitting within the sleeves 2 and the hands within the gloves 3 provided therefor, the head passing up into the helmet 3 where the face is exposed through the opening 23 formed therein, the elasticity of the coat or material of which the garment is composed permitting the head of the wearer 75 to enter the helmet 3 in the desired manner. After arranging the coat over the body as above described, the wearer then steps into the trousers 14 whereupon the garters 19 are fastened, and the belt comprising the sections 12 and 13 arranged one over the other, in which event a water-tight connection is formed between the trousers 14 and the coat 1, this being accomplished by the manipulation 80 of the lever 15 provided for that purpose.

It will be seen from the above, taken in connection with the accompanying drawings, that the casing 6 may be detached from the coat 1 of the garment as occasion 90 demands; that the limbs of the wearer can be moved as desired; and that the light upon the head or top of the helmet will attract attention at night time should the wearer become exhausted or fall asleep.

Dry batteries are arranged within the interior of the garment for supplying the power necessary to the operation of the light 24.

In reduction to practice, I have found that the form of my invention, illustrated in the drawings and referred to in the above description, as the preferred embodiment, is the most efficient and practical; yet realizing that the conditions concurrent with the 100 adoption of my device will necessarily vary, I desire to emphasize the fact that various minor changes in details of construction, proportion and arrangement of parts may be resorted to, when required, without sacrificing any of the advantages of my invention, as defined in the appended claims.

Having thus fully described my invention, what I claim as new and desire to secure by Letters Patent is:

1. In a life preserver, the combination with a coat and trousers, of an undivided non-yielding circumferentially grooved belt section upon said coat, a yieldable divided circumferentially grooved belt section upon said trousers, the latter section adapted to circumferentially inclose the said first section, and means carried by one of said sections operable to draw the said section tight upon the other of the said sections to effect a water-tight joint between the coat and trousers, as and for the purpose set forth.

2. In a life preserver, the combination with a coat and trousers, of a belt section upon said coat, a divided belt section upon

said trousers, the latter section adapted to circumferentially inclose the said first section, and means pivoted to one of the terminals of the said second section and connected to the other terminal of the said second section, operation of said means adapted to draw said second section tight upon said first section to effect a water tight joint between the coat and trousers, as and for the purpose set forth.

3. In a life preserver, the combination with a coat and trousers, and buoyant means carried thereby, of a circumferentially grooved one piece belt section upon said coat, an expandible belt section, correspondingly grooved, secured to said trousers, and means including a lever operable to draw said second section tight upon said first section to effect a water tight joint between the coat and trousers, as and for the purpose set forth.

4. A life preserver including a water proof coat having a helmet formed integrally therewith, the helmet having a face opening formed therein, water proof trousers adapted to be detachably fastened to the said coat,

a pair of removable casings adapted to be disposed upon the interior of the coat near the waist line thereof, a plurality of inflated air tight containers adapted to be arranged within the said casing, a grooved belt section secured to the said coat at the base thereof, a second belt section adapted to conform to the configuration of the said first mentioned belt section secured to the top of the said trousers, the said last mentioned belt section adapted to overlap the said first mentioned belt section for effecting a water tight connection therebetween, a lever pivotally connected to the said last mentioned section adapted to clamp the said section over the said first mentioned section, and means including a pair of adjustable garters arranged exteriorly upon the legs of the trousers, as and for the purpose set forth.

In testimony whereof I affix my signature in presence of two witnesses.

THORSTEIN HIMLE.
